United States Patent Office

Des. 189,749
Patented Feb. 14, 1961

189,749

KNIFE

Joseph V. Miller, Auburn, Mass., assignor to Russell Harrington Cutlery Company, Southbridge, Mass., a corporation of Massachusetts

Filed Nov. 3, 1959, Ser. No. 58,199

Term of patent 14 years

(Cl. D22—3)

Fig. 1 is a side elevational view of a knife showing my new design;

Fig. 2 is a top plan view thereof; and

Fig. 3 is an elevational view of the other side of the knife shown in Fig. 1.

The essential features of my design are shown in full lines in the drawings.

I claim:

The ornamental design for a knife, substantially as shown and described.
